UNITED STATES PATENT OFFICE.

FREDERICK NEWELL MARTINDALE, OF WATERTOWN, NEW YORK.

DESIGN FOR A KETTLE-COVER.

SPECIFICATION forming part of Design No. 27,505, dated August 10, 1897.

Application filed April 8, 1897. Serial No. 631,322. Term of patent 14 years.

To all whom it may concern:

Be it known that I, FREDERICK NEWELL MARTINDALE, a citizen of the United States, residing at Watertown, in the county of Jefferson and State of New York, have invented 5 a new and original Design for a Kettle-Cover, of which the following is a specification.

This invention relates to a new and original design for a kettle-cover; and it has for 10 its object to provide a design of this character that shall be both useful and ornamental.

The leading feature of the design resides in an approximately flat circular body formed at diametrically opposite edges with duplicate 15 offset narrow ears spaced their entire lengths from the peripheral edge of the body and having their terminals disposed in the same direction.

A minor feature of the design resides in 20 forming one half of the body of a smaller diameter than the other half and extending the peripheral edge of the larger half so as to overlap the corresponding edge of the smaller half to produce the narrow ears.

25 In the drawings, Figure 1 is a perspective view of a kettle-cover embodying the herein-described design. Fig. 2 is a plan view thereof. Fig. 3 is a cross-sectional view of the construction illustrated in Figs. 1 and 2. Fig. 4

is a sectional view of a modified form of cover 30 embodying the design.

Referring to the drawings, the numeral 1 designates a circular body, one half of which body is of a smaller diameter than the other half, the separate halves being designated by 35 the numerals 2 and 3, respectively. The peripheral edge of the larger half 3 of the flat circular body 1 is extended to produce narrow ears 4, which are spaced their entire lengths from the peripheral edge of the half 2 of the 40 body concentric with the latter and have their terminals disposed in the same direction.

While in Figs. 1 and 2 the body of the cover is shown entirely flat, in Fig. 4 of the drawings is illustrated a form of cover embodying 45 the design and having a main dished portion and a peripheral flange or rim.

What I claim is—

The design for a kettle-cover, herein shown 50 and described.

In testimony that I claim the foregoing as my own I have hereto affixed my signature in the presence of two witnesses.

FREDERICK NEWELL MARTINDALE.
